UNITED STATES PATENT OFFICE.

AUGUSTUS C. CHASE, OF BEVERLY, MASSACHUSETTS, ASSIGNOR TO UNITED SHOE MACHINERY COMPANY, OF PATERSON, NEW JERSEY, A CORPORATION OF NEW JERSEY.

LOCK-STITCH SEWING-MACHINE.

1,076,951.

Specification of Letters Patent.

Patented Oct. 28, 1913.

Application filed May 10, 1909. Serial No. 495,099.

To all whom it may concern:

Be it known that I, AUGUSTUS C. CHASE, a citizen of the United States, residing at Beverly, in the county of Essex and State of Massachusetts, have invented certain new and useful Improvements in Lock-Stitch Sewing-Machines; and I do hereby declare the following to be a full, clear, and exact description of the invention, such as will enable others skilled in the art to which it appertains to make and use the same.

The present invention relates to sewing machines, and more particularly to curved hook lock stitch sewing machines such as are adapted for use in the manufacture of boots and shoes. In this type of machine, the loop of thread drawn by the needle is passed about the locking thread supply in forming each stitch, and the thread in this loop must be drawn back through the work in setting the stitch. A considerable length of thread must therefore repeatedly render back and forth through the work and through the thread handling devices during the sewing operation, with a resulting tendency to wear and weaken the thread before it enters the seam. This objectionable rendering of the thread may be reduced by reducing the size of the locking thread supply, so that a smaller loop of needle thread is required for the passage of the locking thread supply therethrough, but such reduction in the amount of thread in the locking thread supply necessitates a more frequent replenishing of such supply.

It is the primary object of the present invention to enable frequent replenishing of the locking thread supply without reducing the capacity of the machine and without inconvenience to the operator, so that the use of a minimum length of thread in the locking thread supply is rendered practicable.

To this end the invention contemplates the provision in a lock stitch sewing machine of mechanism for automatically replenishing the locking thread supply, having a novel construction and mode of operation.

In accordance with one feature of the invention, the holder which carries the locking thread supply during the sewing is so mounted that it may be moved from sewing position into position to receive a fresh supply of thread, and a thread supplying mecha-

nism is provided for automatically replenishing the supply of thread in the holder when it is thus moved. Broadly considered, the movement of the thread holder from sewing position into position to receive the fresh supply of locking thread, and the return of the holder to sewing position, may be effected manually or automatically. It is preferred, however, to thus move the thread holder by automatic mechanism which is thrown into operation by the operator, as with such construction the operation of the thread replenishing mechanism is rendered more certain and reliable, and requires less attention on the part of the operator.

The construction of the thread supplying mechanism, or holder for the locking thread supply, is not material to the invention in its broader aspects. It is preferred, however, to carry the locking thread supply upon a bobbin supported within the holder, and it is also preferred to so construct the thread supplying mechanism that it will operate to automatically wind a predetermined length of thread upon an empty bobbin, and to substitute this wound bobbin for an exhausted bobbin in the holder.

In order that a minimum supply of locking thread may be used, the bobbin winding mechanism is preferably so controlled that it will wind upon a bobbin only sufficient thread to sew a single shoe, and in such case the bobbin in the holder is changed after the sewing of each shoe is completed.

To avoid waste of thread, the bobbin winding mechanism is provided with means for measuring the length of thread wound upon the bobbin, and this measuring mechanism in its preferred form is adjustable to vary the length of thread wound upon the bobbin in accordance with the size of shoe to be sewed.

The various features of the invention above outlined, as well as certain further features of invention which are set forth in the claims, will be readily understood from an inspection of the accompanying drawings, in which—

Figure 1 is an elevation, partly in section, showing the left-hand side of a sewing machine embodying the invention in its preferred form; Fig. 2 is a similar view showing the right-hand side of the machine; Fig.

- 2
- 3 is a plan view showing the parts of the front of the machine; Fig. 4 is a front elevation; Fig. 5 is a side elevation looking toward the left, the parts at the right of the bobbin holder and at the right of the bobbin winding mechanism being removed or broken away; Fig. 6 is a detail sectional view on the line 6—6, Fig. 4, looking toward the right; Fig. 7 is a similar view on line 7—7, Fig. 4; Fig. 8 is a similar view on line 8—8, Fig. 4; Figs. 9 to 11 show details of the thread measuring mechanism; Fig. 12 is a rear elevation of the bobbin winding and changing mechanism; Fig. 13 is a longitudinal sectional view on line 13—13, Fig. 12; Fig. 14 is a detail plan view of the bobbin winding mechanism; Fig. 15 is a vertical sectional view through the axis of the shaft shown at the bottom of Fig. 14; Fig. 16 is a detail plan view of the devices at the right-hand end of the bobbin winding and changing mechanism, the parts being broken away for clearness; Fig. 17 is a front elevation of the parts shown in Fig. 16; Fig. 18 is a vertical sectional view on line 18—18, Fig. 16; Figs. 19 and 20 are detail front and side elevations showing the operation of parts of the bobbin winding and changing mechanism; Figs. 21 to 26 inclusive are diagrammatic views showing the mode of operation of the bobbin changing mechanism. Fig. 27 is a front elevation of the bobbin holder removed from its carrier; and Fig. 28 is a sectional view on line 28—28, Fig. 27.
- 35 The various features of the invention are shown in the accompanying drawings embodied in a lock stitch sewing machine having the general construction of the sewing machine shown and described in the patent 40 to French and Meyer, No. 473,870, patented April 26, 1892, to which reference may be had for a complete description of the construction and mode of operation of the parts not specifically described herein.
- 45 The machine shown in the drawings is provided with a work supporting table 1, a presser foot 2, a curved hook needle 3, an awl 4, a looper 5, a thread arm 6, and with main and auxiliary takeups 7 and 8, all of 50 which are constructed and operated as fully described in the patent above referred to. The machine is also provided with a holder 9 for the bobbin, on which the supply of locking thread is wound, and with a thread 55 hook 10 for taking the loop of thread drawn by the needle and carrying it over the bobbin holder. The bobbin holder 9 is provided with a cylindrical recess or opening within which the thread carrying bobbin 11 60 is mounted to rotate. The bobbin is provided with end flanges, and is retained within the recess in the bobbin holder by means of a spring plate 12 provided with grooves for engaging the flanges. The lower end 65 of the bobbin holder is provided with a groove 13 extending inward from the face of the bobbin holder through which the thread leads from the bobbin to the work during the sewing operation. One side of the groove 13 is formed by a block 14 which is carried by the lower end of a spring arm 15, and is forced yieldingly toward the opposite side of the groove to frictionally clamp the thread passing through the groove and apply the proper tension to the thread. The upper end of the bobbin holder is shaped to form a pointed loop receiving nose 16 over which the loop of thread drawn by the needle is delivered by the thread hook 10. The bobbin holder is supported in fixed position in the outer end of a carrier 17, the front end of the carrier being provided with a retaining frame or cage 18 within which the bobbin holder is loosely supported, so that the loop of thread delivered over the nose of the holder by the thread hook may pass down around the bobbin holder.
- 70 75 80 85 90 95 100 105 110 115 120 125 130
- The thread hook 10 consists of a curved finger extending rearwardly from the lower end of a shaft 19 which is mounted in the front end of a lever 20. The shaft 19 is provided with spiral grooves or threads engaging threads formed in a nut secured in the end of the lever 20, and the upper end of the shaft is connected by a universal joint 21 to the front end of a second lever 22. The lever 22 is pivoted at 23 upon the lever 20, and is provided at its rear end with a roll playing within a cam slot 24 which is formed in a fixed plate 25. The thread hook lever 20 is rocked at proper intervals during the operation of the machine by a cam 26 secured to the cam shaft 27 of the machine, and arranged to engage a roll 28 which is carried by a lever 29. The front end of the lever 29 is connected by a pin and slot connection 30 with the rear end of the thread hook lever 20.
- When the curved hook needle has drawn the loop of thread through the material, the front end of the thread hook lever 20 is moved upward. During the first part of the upward movement of the lever, the lower end of the thread hook 10 engages the loop of thread and carries it upward. The cam slot 24 is of such shape that during this first part of the upward movement of the thread hook the lever 22 moves with the lever 20, while during the latter part of the upward movement of the lever 20, the nut at the front end of the lever moves up the shaft 19, thus swinging the thread hook 10 forward so that it delivers the loop of thread over the nose of the bobbin holder. When the lever 20 is returned to normal position, the nut at the front end of the lever first slides down the shaft 19, swinging the hook 10 back, and then the continued movement of the lever carries the hook down into position to receive the next loop drawn by the

needle. The loop of thread delivered over the nose of the bobbin holder passes down over the bobbin holder, the cage or frame 18 in which the holder is mounted being open at its front for the passage of the legs of the loop, and being shaped to allow the loop to readily pass down over the holder.

In addition to the stitch forming instrumentalities, the machine illustrated is provided with mechanism for automatically replenishing the supply of thread in the bobbin holder when the supply becomes exhausted. In its preferred form this mechanism includes mechanism for winding a supply of thread upon an empty bobbin preparatory to the substitution of a full bobbin for the bobbin in the holder. In the construction shown the bobbin winding and changing mechanism is arranged above the thread handling devices of the sewing mechanism, and the bobbin holder is moved up from its normal or sewing position into position to coöperate with the bobbin changing mechanism when the supply of thread in the bobbin holder has become exhausted. To enable the bobbin holder to be thus moved, the carrier 17 for the bobbin holder is secured to a rock shaft 31, and is normally supported in fixed position upon a supporting plate 32. The rock shaft 31 is provided at one end with a pinion 33 which is engaged by a gear segment 34 formed on the lower end of a lever 35 the upper end of which is pivoted at 36. The lever is provided with a roll 37 engaging a cam groove 38 formed in the cam drum 39 of the bobbin winding and changing mechanism.

The bobbin winding and changing mechanism is provided with a bobbin winding spindle 40 which carries a full bobbin when the mechanism is at rest in normal position. The bobbin winding spindle is provided at its front end with a projecting pin 41 for engaging the bore of the bobbin, the end of the pin being split to form spring fingers for frictionally holding the bobbin on the pin. The pin is formed on the outer end of a rod 42 which extends through a recess formed in the end of the spindle, and is held in normal position by a spring 43 interposed between the bottom of the recess and a collar 44 formed on the rod. The spring acts to hold the collar against a block 45 which is screwed into the front end of the recess in the spindle. The front end of the spindle is also provided with a sleeve 46 which is split longitudinally to form a series of spring jaws for engaging the flange on the bobbin and securing it to the spindle. A second sleeve 47 surrounds the sleeve 46 and is retained within a recess in the bearing 48 by a plate 49. The sleeve 46 is provided with a tapered enlargement 50 which coöperates with the inner surface of the sleeve 47 in forcing

the spring sections of the sleeve 46 firmly into engagement with the flange of the bobbin when the sleeve 46 is within the sleeve 47, as indicated in Fig. 13. The outer end of the sleeve 46 is also provided with a radially projecting flange which coöperates with the outer end of the sleeve 47 in clamping the end of the supply thread previous to the winding of the bobbin, as will be hereinafter more fully explained. The winding spindle 40 is mounted to rotate and slide longitudinally within a bearing sleeve 51 which is secured within the bearing 48, and within the split bearing 52. The longitudinal movements are imparted to the spindle through a reciprocating slide 53, the end of which is connected by means of a stud 54 with the rear end of the spindle. A washer 55 is interposed between the end of the spindle 51 and the bearing 56 at the end 80 of the slide 53 in which the stud 54 turns, and the spindle is held against longitudinal movement with relation to the slide 53 by a spring 57 interposed between the head of the stud 54 and a series of washers 58 which are interposed between the spring and the bearing 56. The spindle 40 is normally stationary, and is rotated at the proper intervals and during the proper periods through a pulley 59 keyed to the spindle and held against longitudinal movement by a sleeve 60 which is screwed on to the hub of the pulley, and is provided with a rib 61 arranged between the bearing 52 and a flange 62 on the end of the sleeve 51. The pulley 59 is connected by a belt 63 with a pulley 64, which is secured to the end of a shaft 65 mounted in suitable bearings and parallel with the bobbin winding spindle. One member 66 of a driving clutch is keyed to the shaft 65, and is arranged to engage and be driven by a clutch member 67 secured to a sleeve 68 which surrounds the shaft 65. The sleeve 68 and connected clutch member 67 are continuously driven through a pulley 69 which is secured to the sleeve 68, and is connected by a belt 70 with a pulley 71. The pulley 71 is secured upon a shaft 72 arranged at the rear of the machine, and provided with a worm wheel 73 which is engaged by a worm 74 on a driving shaft 75. The shaft 75 is continuously driven by means of a belt 76 passing over the pulley 77 secured to the shaft. The clutch member 66 is forced in a direction to engage the continuously rotating clutch member 67 by a spring 78 surrounding the hub of the clutch member 66. The clutch is held out of engagement against the tension of the spring 78 by means of a yoke lever 79, provided with arms on its upper end which carry rolls engaging a flange 80 on the clutch member 66. The lower end of the yoke lever is provided with a laterally projecting lug 81, and this lug is normally en-

gaged by a latch 82 which holds the lever in position to retain the clutch member 66 out of engagement (Figs. 7, 14 and 15).

The latch 82 is operated at the proper time by mechanism to be described to release the yoke lever 79, and when this occurs the clutch members 66 and 67 are engaged, and the winding spindle is rotated to wind the thread upon the bobbin carried by the spindle. This rotation continues until the yoke lever 79 is operated by a thread measuring mechanism to be herein-after described to disengage the clutch 66. When this occurs the rotation of the winding spindle ceases, and the latch 82 re-engages the lug 81 and retains the winding clutch out of engagement.

When the parts are in normal position the thread *t* leads from the bobbin on the end of the winding spindle through a thread guiding eye 83, between the fixed and movable jaws 84 and 85 of a thread gripper, is wound about the measuring wheel 86 of the thread measuring mechanism, and passes through a tube 87 and about a guide roll 88, and through a suitable tension device to the thread supply. The thread guiding eye 83 is formed at the outer end of an arm 89, which is pivotally supported at 90 upon the front end of a carrier plate 91 which is secured to a rock shaft 92. The fixed jaw 84 of the thread gripper is formed on the end of the arm 89 directly above the thread eye 83, and the movable jaw 85 of the gripper is formed on the outer end of a lever which is pivoted to the arm 89 at 93. The gripper jaws are held normally open by means of a leaf spring 94 arranged to engage the rear end of the gripper lever. The gripper is closed at the proper time by means of a pin 95 passing through the pivot 90 of the thread eye and gripper arm, and provided at its lower end with a conical head 96. When the pin 95 is raised in the manner hereinafter described, the upper end of the pin acting upon the gripper lever operates the lever to grip the thread between the jaws 84 and 85, and the gripper is locked in closed position by means of a latch block 97, the front end of which is arranged to pass under a flange 98 on the pin 95 when the pin is raised. The latch block is forced forward by means of a spring 99 when the pin 95 is raised, so that the front end of the latch block passes under the flange 98 and holds the gripper closed until the latch block is withdrawn by the means to be hereinafter described. The thread eye and thread grippers are moved toward and from the winding spindle by rocking the shaft 92, and are moved laterally about the pivot 90 for a purpose which will be explained hereinafter. The rocking of the shaft 92 is effected by the cam groove 38 which operates the carrier for the bobbin holder, as already explained. This cam

groove is engaged by a roller 100 on the lower end of a lever 101 which is pivotally mounted upon a shaft 102. The upper end of the lever 101 is curved over the shaft 92, as indicated in Fig. 7, and is connected by a link 103 with an arm 104 secured to the shaft. The lateral movement of the thread eye and grippers is effected by means of a cam groove 105 formed in a fixed plate 106, and engaged by a pin 107 secured in the arm 89 at the rear of the pivot 90 (Figs. 5, 18, 19 and 20).

The length of thread wound upon the bobbin is determined by a measuring mechanism operated from the wheel 86 about which the thread passes on its way to the bobbin. This mechanism operates to disengage the winding clutch 66 after a predetermined length of thread has been wound upon the bobbin, and is best illustrated in Figs. 3, 4, 6 to 11, 14 and 15. As shown in Fig. 15, the wheel 86 about which the thread is wrapped is mounted to turn freely upon the shaft 65, and the hub of the wheel is provided with a worm 108 engaging a worm wheel 109. The worm wheel is mounted upon a sleeve 110 (Fig. 8), which is in turn mounted in a fixed bearing 111 and surrounds a fixed stud 112. The worm wheel is provided in its rear face with an annular groove 113 arranged to receive a segmental clutch block 114 which is secured to a segmental trip plate 115. The free end of the clutch block 114 is split to form two spring clamping jaws which normally spring toward each other so that the block may slide freely in the annular groove 113 (Figs. 10 and 15). The jaws of the clutch block are operated to grip the walls of the groove 113 and thus connect the trip plate 115 with the worm wheel by a cam 116 arranged between the ends of the jaws, and formed upon a rock shaft 117 which is mounted in the trip plate. The rock shaft 117 is operated to spread and release the jaws of the clutch block through an arm 118 which projects radially from the rock shaft and is provided with a laterally projecting pin 119. The trip plate 115 is mounted to turn freely upon the stud 112, and is provided with a hub upon which a torsional spring 120 is supported. One end of this spring is secured to the trip plate, and the other end of the spring is secured to a collar 121 which is adjustably secured to the stud 112. The spring tends to turn the trip plate 115 toward the right in Figs. 4 and 10, or in a direction opposite to that in which the worm wheel 109 is turned by the rotation of the measuring wheel 86. The trip plate is provided with a laterally projecting pin 122 arranged to engage the end of the yoke lever 79, and to operate the lever to disengage the winding clutch 66.

The parts of the thread measuring mechanism are normally in the positions indicated

in the drawings. Just before the latch 82 is operated to release the yoke lever 79 and engage the winding clutch, an arm 123 which is secured upon the rock shaft 102 is raised, so that an inclined cam surface 124 on the end of the arm acts upon the pin 119 to rock the shaft 117 and thus release the clutch block from clamping engagement with the walls of the groove 113 in the worm wheel 109. When this occurs the spring 120 immediately acts to shift the clutch block and trip plate 115 toward the right in Fig. 10, and this movement of the clutch block and trip plate continues until the arm 118 strikes a stop 125. The engagement of the arm 118 with the stop 125 rocks the arm 118 and rock shaft 117, so that the cam 116 forces the jaws of the clutch block into clamping engagement with the walls of the groove 113. Shortly after the clutch block and trip plate are shifted, a second arm 126 (Fig. 7) which is secured to the rock shaft 102 is raised, and engages a pin 127 on the latch 82, operating said latch to release the yoke lever 79, so that the winding clutch is engaged. The winding spindle is now operated to wind the thread upon the bobbin carried by the spindle, and as the wheel 86 is rotated by the thread, the worm wheel 113 and the connected clutch block and trip plate are advanced or moved toward the left in Fig. 10. This movement continues until the pin 122 engages the yoke lever 79 and operates the lever to disengage the winding clutch. The rock shaft 102 is operated at the proper intervals and to the proper extent through two arms 136 and 137 which are secured to the shaft and are arranged to be engaged by two pins 138 and 139 carried by the cam drum 39 (Figs. 4 and 6). The engagement of the pin 139 with the arm 137 does not rock the shaft 102 sufficiently to bring the arm 126 into engagement with the pin 127 of the latch 82, while the engagement of the pin 138 with the arm 136 rocks the shaft sufficiently to cause the arm 126 to operate the latch 82.

In the construction shown the bobbin winding mechanism is constructed to wind the proper length of thread upon the bobbin to sew a single shoe. In order to avoid a waste of thread, means are provided for varying the length of thread wound by the winding mechanism, in accordance with the size of the shoe to be sewed. In the construction shown, the variation in the length of the thread according to the size of the shoe to be sewed, is secured by adjustment of the stop 125, the position of which determines the distance through which the trip plate moves during the winding of the thread upon the bobbin, and consequently determines the length of thread which passes over the measuring wheel 86 before the winding clutch is thrown out of action. In

the construction shown, the stop 125 is formed on the end of an arm 128 extending radially from the inner end of the sleeve 110, and an adjusting arm 129 is secured upon the outer end of the sleeve. The arm 129 is provided with a spring pressed locking pin 130, the inner end of which is arranged to engage any one of a series of holes 131 formed in a disk 132 which is secured to the front face of the bearing 111. A disk 133 is formed on the arm 129, and is provided with a line or pointer 134 which co-operates with a scale 135 on the disk 132 in indicating the proper adjustment for the various sizes of shoes to be sewed.

The bobbin changing mechanism comprises means for transferring the bobbin upon which the thread has been wound by the bobbin winding mechanism to the bobbin holder, and transferring the empty bobbin in the holder to the winding spindle, so that a fresh supply of thread may be wound upon the empty bobbin. In effecting this transfer, the bobbin, a carried by the end of the winding spindle is first transferred to a bobbin holding stud 140 which is arranged in line with the bobbin winding spindle, and is carried by an arm 141 which projects forward from a reciprocatory slide 142 (Figs. 12 and 13). The bobbin receiving stud 140 is split to form spring fingers which frictionally engage the bore of the bobbin and retain the bobbin on the stud. Reciprocatory movements are imparted to the bobbin winding spindle and to the bobbin receiving stud in changing the bobbin, by a cam groove 143 formed in the periphery of the cam drum 39, and arranged to operate upon a roller 144 which is secured to the slide 142. The inner end of the slide 142 is provided with a rack 145 which engages a gear segment 146. The disk on which the gear segment 146 is formed is provided with a second gear segment 147 of smaller diameter, which engages a rack 148 formed on the inner end of the slide 142 to which the winding spindle is connected. By these connections the slides 142 and 53 are simultaneously moved in opposite directions to bring the end of the winding spindle and the bobbin receiving stud toward or away from each other, the movement imparted to the winding spindle being one-half that imparted to the bobbin receiving stud. The slide 142 also carries the devices for severing the bobbin thread from the thread supply and gripping the end of the thread, and also the devices for inserting the bobbin thread into the tension slot of the bobbin holder.

The devices for severing the bobbin thread from the thread supply, and gripping the end of the thread, consist of a fixed gripper jaw 149 carrying a cutter blade 150, and a cooperating movable gripper jaw 151. The

movable gripper jaw is formed on the end of a lever pivoted at 152, and having its rear end connected by a link 153 with the front end of an operating lever 154. The lever 154 is operated to open the grippers by means of a bell crank lever 155 which is mounted upon a fixed pivot 156, and is so arranged that one arm of the lever is engaged by the rear end of the lever 154 during the advance movement of the slide 142. The bell crank lever 155 is held in normal position by a spring pressed pin 155' arranged to bear against the rear arm of the lever. The grippers are closed by a pin 157 having one end arranged to engage the front end of the lever 154, and having its other end arranged to be brought into engagement with the plate 91 which carries the thread eye and gripper heretofore described, during the advance movement of the slide 142.

The device for introducing the thread into the tension slot of the bobbin holder comprises a plate 158 carried by the arm 141 and arranged to enter the tension slot of the bobbin holder during the advance of the slide 142. A thread guiding finger 159 may also be provided for directing the thread into the slot, and when used acts in the nature of a safety device for insuring the engagement of the thread with the slot. The mode of operation of these devices will be more fully explained in the description of the general mode of operating of the bobbin winding and changing mechanism.

The cam drum 39 which operates and controls the various parts of the bobbin winding and changing mechanism, is driven at the desired intervals through a clutch 40 which is thrown into operation at the will of the operator, and which drives the cam drum through a single revolution, and is then automatically thrown out of action. In the construction shown, this clutch comprises a spring pressed pawl 160 pivotally mounted on one end of the drum 39, and arranged to engage a series of ratchet teeth 161 formed on a sleeve 162 which is mounted to turn freely about the bearing sleeve 51 (Figs. 4, 6 and 13). The ratchet sleeve 162 is continuously driven from a pulley 69 through a gear 163 formed on the hub of the pulley, and engaging an intermediate gear 164 which engages a gear 165 secured to the ratchet sleeve. The pawl 160 is normally held out of engagement with the ratchet against the tension of its spring 166 by a trip lever 167, the lower end of which is arranged to engage the tail of the pawl and hold it against a stop pin 168. The trip lever is pivotally supported at 169, and the upper end of the lever is engaged by a spring 170 which tends to hold the lower end of the lever in the path of the pawl 160. The trip lever is operated to release

the pawl so that it will engage the ratchet teeth 161 by a trip dog 171 pivoted upon a lever 172. The trip dog is normally held in position to engage the upper end of the trip lever by a spring 173 which holds the upper end of the trip dog against a stop pin 174. The lever 172 projects forward and is provided with a handle 175, so that it may be conveniently operated by the operator. The lever may also be connected, as indicated in Fig. 1, with a slide 176 which is connected through a rod 177 with a treadle (not shown). When the lever 172 is operated, either through the handle 175, or through the treadle connected with the slide 176, the dog 171 strikes the upper end of the trip lever 167, rocking the lever so that it releases the pawl 160 and allows the pawl to engage the ratchet teeth 161. The cam drum 39 is now rotated in the direction of the arrow, Fig. 6. After the dog 171 has operated the trip lever, continued movement of the lever 172 causes the dog to disengage the upper end of the trip lever, so that the lever is returned into the path of the pawl 160. When the drum has made a complete revolution, the tail of the pawl strikes the end of the lever, thus disengaging the pawl and arresting the rotation of the drum.

In order to insure the disengagement of the clutch pawl 160, after the cam drum has made a single revolution, a safety device is provided for disengaging the trip dog 171 from the upper end of the trip lever, and returning the trip lever to normal position in case the lever 172 has not been returned to normal position, and the dog 171 has failed to disengage the upper end of the trip lever. This safety device comprises a lever 178 mounted on the pivot 169, and provided at its upper end with a pin 179 for engaging the latch dog 171. The lower end of this lever is arranged to be engaged by the pin 139. As the cam drum 39 rotates, the pin 139 strikes the lower end of the lever 178, rocking the lever so that the pin 179 will operate to lift the latch dog 171 and disengage it from the upper end of the trip lever 167. This will insure the return of the latch lever 167 to normal position, even if the operator has not released the lever 172, or has not moved the lever sufficiently to disengage the dog.

When the bobbin mechanism is thrown into operation by the operator, the stitch forming instrumentalities should be in such position that they will not interfere with the movement of the bobbin holder. In order that the bobbin changing mechanism may not inadvertently be thrown into operation when the sewing instrumentalities are not in proper position, means is provided for determining the position of the sewing mechanism when the bobbin mechanism is

thrown into action. In the construction shown this means consists of a recess 180 formed in the face of one of the cams 181 which is secured to the cam shaft of the machine, and arranged to register with an arm 182 on the clutch controlling lever 172, when the sewing mechanism is in proper position for the operation of the bobbin changing mechanism. When this recess is in register with the arm on the clutch operating lever, the lever 172 may be shifted to throw the bobbin changing mechanism into operation, the arm 182 entering the recess as the lever is operated. If the recess 180 is not in register with the arm 182, the arm will strike the periphery of the cam 181, in case it is attempted to operate the clutch controlling lever 172, and will prevent a movement of the lever sufficient to throw the bobbin changing mechanism into operation. The recess 180 is so located upon the cam 181 that the sewing mechanism is in proper position for the operation of the bobbin changing mechanism when this recess is in register with the arm 182.

The operation of the mechanism is as follows. After a shoe has been sewed, the machine is brought to rest with the stitch forming mechanism in proper position for the removal of the work and for the introduction of another shoe into position to be operated upon by the sewing mechanism. At this time the recess 180 in the cam 181 is in position to allow the bobbin changing mechanism to be thrown into action. The operator now throws the driving clutch into operation by moving the clutch actuating lever 172 either by means of the handle 173, or by depressing the treadle connected with the lever. The cam drum 39 now makes a single revolution and then stops. During the first part of the revolution of the cam 39, the slides 52 and 142 are operated to move the bobbin winding spindle 40 and the bobbin receiving stud 140 toward each other. During this movement of the winding spindle the conical projection 50 on the sleeve 46 at the end of the spindle is disengaged from the sleeve 47, so that the spring jaws which grip the flange of the bobbin *a* spring outward and release the bobbin. The combined movement of the bobbin winding spindle and bobbin receiving stud carries the bobbin on to the bobbin receiving stud, the bobbin holding pin 41 in the end of the bobbin winding spindle yielding to allow the bobbin holding stud 140 to enter the bore of the bobbin. The bobbin *a* is thus transferred to the bobbin holding stud, as indicated in Fig. 22. During this advance movement of the slide 142, the gripper jaws 149 and 151 have passed on opposite sides of the thread *t* between the thread guiding eye 83 and the bobbin. During this forward movement of the slide 142, a finger 183 se-

cured to the slide 142 strikes the rear end of the bell crank lever 155 and swings the end of the lever out of the path of the gripper opening lever 154, so that the rear end of the lever 154 passes in front of the arm of the lever 155. As the slides 52 and 142 complete their advancing movements, the pin 157 strikes the plate 91 and is operated to close the gripper jaws 149 and 151. When the gripper is thus closed, the thread is severed by the knife 150 a short distance below the thread guiding eye 83, and the end of the bobbin thread is gripped by the jaws 149 and 151. As the slides complete their forward movement, a plate 184 on the arm 141 rides under the conical lower end 96 of the pin 95, raising the pin to operate the gripper 85, so that the supply thread is gripped between the jaws 84 and 85 immediately above the thread guiding eye 83, the latch slide 97 moving forward under the flange 98 on the pin 95 to lock the jaw 85 in closed position.

During the continued rotation of the cam drum 39, the slides 52 and 142 are returned to their normal position, the bobbin *a* remaining on the bobbin carrying stud as indicated in Fig. 23. The cam slot 38 now operates the lever 35 to swing the carrier for the bobbin holder up into position to bring the recess in the bobbin holder in line with the bobbin *a*, the nose of the bobbin holder engaging a gage plate 185 on the slide 142. This position of the parts is indicated in Fig. 24. The slides 52 and 142 are now again advanced as indicated in Fig. 25. The advance movement of the slides at this time is sufficient to carry the full bobbin *a* which is on the bobbin carrying stud 140 into the bobbin holding recess of the bobbin holder. As the bobbin *a* is carried forward into the bobbin holder, it pushes the empty bobbin *b* on to the bobbin holding pin 41 of the bobbin winding spindle, the spring which backs up the pin being sufficiently stiff to hold the pin against the friction of the bobbin as it is forced on to the spring fingers at the end of the pin. During this advance movement of the slide 142, the thread which extends from the thread gripping jaws to the bobbin is engaged by the front end of the plate 158, and is pressed into the tension slot 13 of the bobbin holder, as indicated in Fig. 25.

The finger 183 is arranged to engage the thread between the bobbin and the gripping jaws as the bobbin enters the bobbin holder, and acts to insure the entrance of the thread into the tension slot. As the slide 142 completes its forward movement, the rear end of the gripper opening lever 154 strikes the arm of the bell crank lever 155, thus opening the grippers to release the end of the bobbin thread. The advance movement of the slide is not sufficient at this time to bring the finger 183 against the rear arm of the bell

crank lever, or to operate the gripper closing pin 157. The slides 53 and 142 now start to return to their normal position. During the retraction of the slides, the plate 5 carrying the thread guiding eye 83, and gripping jaws 84 and 85, is swung downward as indicated in Fig. 20, to carry the end of the supply thread between the flange on the sleeve 46 and the end of the sleeve 47. 10 During the downward movement of the thread eye and gripper the arm 89 is swung laterally, as indicated in Fig. 19, to bring the thread into position to be gripped between the flange on the sleeve 46 and the end 15 of the sleeve 47. As the slides 53 and 142 complete their return movement, the end of the supply thread is gripped between the flange on the sleeve 46 and the end of the sleeve 47, as indicated in Fig. 26, and the spring sections of the sleeve 46 are forced inward to firmly grip the flange of the empty bobbin and secure it to the end of the winding spindle. During this return movement of the slides the grooves in the 25 spring plate 12 of the bobbin holder retain the bobbin *a* within the holder as the bobbin carrying stud 140 recedes. Immediately after the empty bobbin has thus been removed from the bobbin holder, and the full bobbin introduced into the bobbin holder, the carrier for the bobbin holder is swung down to bring the bobbin holder into normal or sewing position. After the end of the supply thread has been gripped, the latch block 97 30 is forced back to release the gripping jaw 85 by a pin 185 which projects laterally from an arm 186 secured to the rock shaft 102, and is arranged to engage a lug 187 on the side of the latch block. The plate 91 is 35 then swung upward to return the thread guiding eye 83 to normal position, the cam slot 105 acting on the pin 107 to swing the thread eye laterally into line with the center of the empty bobbin. The movement 40 of the rock shaft 102, which brings the pin 185 into engagement with the lug 187 on the latch block 97, and releases the gripping jaw 85, preparatory to the return of the thread guiding eye 83 to normal position, raises 45 the arm 123 to release the clutch block 114 of the thread measuring mechanism, so that the said block and the clutch tripping plate 115 are moved into position against the stop 125 preparatory to the winding of the thread 50 upon the empty bobbin. Immediately thereafter the shaft 102 is rocked to a greater extent to operate the latch 82 and release the yoke lever for the winding clutch 66, so that the winding clutch is engaged, and the 55 bobbin winding spindle is rotated to wind the proper length of thread upon the bobbin. When the proper length of thread has been wound upon the bobbin, the bobbin winding clutch is thrown out of action in 60 the manner already described. The parts 65

are now in their normal position, ready to be thrown into operation by the operator when the bobbins are to be again changed.

The mechanism for automatically replenishing the supply of locking thread in the 70 locking thread holder enables the locking thread supply to be replenished after the sewing of each shoe is finished, without involving any material reduction in the capacity of the machine, since the operator may 75 throw the bobbin winding and changing mechanism into operation as he is removing a shoe from the machine, and the changing of the bobbins and the return of the bobbin holder to sewing position, will be effected 80 during the interval while he is introducing another shoe into position to be sewed. The winding of the supply of thread upon the empty bobbin may be completed during the 85 sewing of this shoe.

While it is preferred to employ the specific construction and arrangement of parts shown and described, since this construction and arrangement is well adapted for application to the machine illustrated in the patent above referred to, it will be understood that this construction and arrangement is not essential except as defined in the claims, and may be varied and modified as found desirable and in accordance with the construction and arrangement of the parts of the sewing machine in which the invention 90 is to be embodied.

Having set forth the nature and object of the invention, and specifically described one 100 form of machine in which it may be embodied, what I claim is:—

1. A lock stitch sewing machine, having, in combination, stitch forming devices including a holder for the locking thread supply, a carrier for the holder stationary during the sewing and mounted for movement to carry the holder from sewing position into position to coöperate with a thread supplying mechanism, and a thread supplying mechanism for replenishing the supply of thread in the holder, substantially as described.

2. A lock stitch sewing machine, having, in combination, stitch forming devices including a holder for the locking thread supply, a thread supplying mechanism, mechanism acting automatically to move the holder from sewing position into position to coöperate with the thread supplying mechanism and return it to sewing position, and mechanism for actuating the thread supplying mechanism to replenish the supply of thread in the holder, substantially as described.

3. A lock stitch sewing machine, having, in combination, stitch forming devices including a bobbin holder for the locking thread supply movable from sewing position into position to coöperate with a bobbin changing mechanism, and a bobbin 125

changing mechanism, substantially as described.

4. A lock stitch sewing machine, having, in combination, stitch forming devices including a bobbin holder for the locking thread supply, a bobbin changing mechanism, mechanism acting automatically to move the bobbin holder from sewing position into position to coöperate with the bobbin changing mechanism and to return it to sewing position, and mechanism for actuating the bobbin changing mechanism to substitute a full bobbin for an empty bobbin in the holder, substantially as described.

5. A lock stitch sewing machine, having, in combination, stitch forming devices including a bobbin holder for the locking thread supply, a bobbin winding and changing mechanism, mechanism for moving the bobbin holder from sewing position into position to coöperate with the bobbin changing mechanism, and mechanism for actuating the bobbin winding and changing mechanism to transfer the empty bobbin in the holder to the bobbin winding mechanism and introduce a full bobbin into the holder, and for actuating the bobbin winding mechanism to wind a supply of thread upon the empty bobbin, substantially as described.

6. A lock stitch sewing machine, having, in combination, stitch forming devices including a holder for the locking thread supply, mechanism acting automatically under the control of the operator to replenish the supply of thread in the holder, and means for preventing the operation of the replenishing mechanism when the stitch forming devices are out of a predetermined relation to each other, substantially as described.

7. A lock stitch sewing machine, having, in combination, stitch forming devices including a holder for the locking thread supply, mechanism for replenishing the supply of thread in the holder, means under the control of the operator for throwing the replenishing mechanism into operation, and means for preventing the throwing of the replenishing mechanism into operation when the stitch forming devices are out of a predetermined relation to each other, substantially as described.

8. A lock stitch sewing machine, having, in combination, stitch forming devices including a bobbin holder for the locking thread supply provided with a bobbin holding recess extending through from one side to the other of the holder shaped to allow the bobbin to pass through the holder whereby the bobbin may be introduced at one end of the recess and discharged through the other in substituting a full bobbin for an empty bobbin in the holder, substantially as described.

9. A lock stitch sewing machine, having, in combination, stitch forming devices in-

cluding a bobbin holder for the locking thread supply provided with a bobbin holding recess extending through from one side of the holder to the other, and mechanism for introducing a bobbin at one end of the recess to replace the bobbin discharged thereby through the opposite end of the recess, substantially as described.

10. A bobbin winding and changing mechanism for lock stitch sewing machines, having, in combination, a bobbin winding mechanism, a bobbin receiving device, and mechanism for actuating the bobbin winding mechanism and bobbin receiving device to wind a supply of thread upon a bobbin and transfer the wound bobbin to the bobbin receiving device, and to thereafter transfer the wound bobbin from the bobbin receiving device to a holder for the locking thread supply, substantially as described.

11. A bobbin winding and changing mechanism for lock stitch sewing machines, having, in combination, a bobbin winding spindle provided with devices for holding the bobbin thereon, a bobbin receiving stud arranged in line with the bobbin winding spindle, and means for relatively actuating the spindle and stud to transfer a bobbin from the spindle to the stud, and means for transferring the wound bobbin from the stud to a bobbin holder, substantially as described.

12. A bobbin winding and changing mechanism for lock stitch sewing machines, having, in combination, a bobbin winding spindle, devices for securing a bobbin to the spindle, a bobbin receiving stud arranged in line with the spindle, means for actuating the spindle to wind a supply of thread upon the bobbin, mechanism for relatively actuating the spindle and stud to transfer the bobbin to the stud, a bobbin holder, and mechanism for relatively actuating the bobbin holder, bobbin stud and winding spindle to transfer the bobbin from the stud to the holder, and to transfer a bobbin within the holder to the winding spindle, substantially as described.

13. A bobbin winding and changing mechanism for lock stitch sewing machines, having, in combination, a bobbin winding spindle, devices for securing a bobbin upon the spindle, means for actuating the spindle to wind a supply of thread upon the bobbin, devices for severing the thread from the thread supply and removing the bobbin from the spindle, and means for connecting the end of the thread supply with the spindle and guiding the thread to a bobbin secured to the end of the spindle, substantially as described.

14. A lock stitch sewing machine, having, in combination, a bobbin holder for the locking thread supply, a bobbin winding and changing mechanism comprising a bobbin winding spindle, devices for securing a bob-

bin on said spindle, mechanism for actuating said spindle to wind a supply of thread upon the bobbin, devices for severing the thread from the thread supply and removing the wound bobbin from said spindle, and means for actuating said devices to introduce the wound bobbin into the bobbin holder and transfer the empty bobbin from the holder to said winding spindle, substantially as described.

15. A lock stitch sewing machine, having, in combination, stitch forming devices including a bobbin holder for the locking thread supply, a bobbin winding mechanism, mechanism operated by the thread for measuring the length of thread wound upon the bobbin by the bobbin winding mechanism, and mechanism for transferring a wound bobbin from the bobbin winding mechanism to the bobbin holder, substantially as described.

16. A lock stitch shoe sewing machine, having, in combination, stitch forming devices including a curved hook needle and a bobbin holder for the locking thread supply, a bobbin winding mechanism, means for operating the winding mechanism to wind thread upon the bobbin of a length necessary to attach the sole of a single shoe only, and mechanism for introducing the wound bobbin into the bobbin holder, substantially as described.

17. A lock stitch shoe sewing machine, having, in combination, stitch forming devices including a bobbin holder for the locking thread supply, bobbin winding mechanism having provision for varying the length of thread wound upon the bobbin in accordance with the size of the shoe to be sewed, and mechanism for transferring a wound bobbin from the bobbin winding mechanism to the bobbin holder, substantially as described.

18. A lock stitch sewing machine, having, in combination, stitch forming devices including a bobbin holder for the locking thread supply provided with a tension slot, bobbin supporting devices provided with a thread gripper for holding the free end of the bobbin thread, means for relatively actuating the bobbin holder and the bobbin supporting devices to bring the bobbin into register with the bobbin holding recess of the holder, and the thread leading from the thread gripper to the bobbin into register with the tension slot, and means for relatively actuating the bobbin holder and bobbin supporting devices to introduce the bobbin into the holder and the thread leading from the bobbin to the grippers into the tension slot, substantially as described.

19. A lock stitch sewing machine, having, in combination, stitch forming devices including a bobbin holder for the locking thread supply, a bobbin winding spindle

provided with devices for securing a bobbin thereto, bobbin receiving devices arranged in line with the bobbin winding spindle, mechanism for relatively actuating the bobbin winding spindle and bobbin receiving devices to transfer a wound bobbin from the bobbin spindle to the bobbin receiving devices, mechanism for relatively actuating the bobbin holder and the bobbin winding spindle and receiving devices to bring the bobbin holder into position between the bobbin winding spindle and bobbin receiving devices, and mechanism for relatively actuating the bobbin winding spindle and bobbin receiving devices to transfer the bobbin on the bobbin receiving devices to the bobbin holder, and transfer the replaced bobbin in the bobbin holder to the bobbin winding spindle, substantially as described.

20. A lock stitch sewing machine, having, in combination, stitch forming devices including a bobbin holder for the locking thread supply, bobbin winding devices and bobbin receiving devices arranged in line with each other, mechanism for actuating the bobbin winding devices to wind a length of thread upon a bobbin, mechanism for relatively actuating the bobbin winding and receiving devices to sever the bobbin thread from the thread supply and transfer the wound bobbin to the bobbin receiving devices, and mechanism for relatively actuating the bobbin holder and bobbin winding and receiving devices to bring the bobbin holder into position between the bobbin winding and receiving devices and to introduce the wound bobbin into the holder and transfer the replaced bobbin from the holder to the winding devices, substantially as described.

21. A lock stitch sewing machine, having, in combination, stitch forming devices including a holder having a transverse bobbin holding recess, a bobbin changing mechanism, and a carrier for the holder stationary during the sewing and movable to bring the holder into register with the bobbin changing mechanism or into the position where it will coöperate with the other stitch forming devices during the sewing operation, substantially as described.

22. A lock stitch sewing machine, having, in combination, stitch forming devices including a curved hook needle and a bobbin holder, a carrier for the holder stationary during the sewing and mounted for movement out of and into the position it occupies during the sewing operation, and a thread supplying mechanism for replenishing the supply of thread in the holder when the holder is out of sewing relation with the needle, substantially as described.

23. A lock stitch sewing machine, having, in combination, stitch forming devices including a holder for the locking thread supply stationary during the operation of the

sewing mechanism and mounted for movement from sewing position into position to coöperate with the thread supplying mechanism, and a thread supplying mechanism for replenishing the supply of thread in the holder, substantially as described.

In testimony whereof I affix my signature, in presence of two witnesses.

AUGUSTUS C. CHASE.
